UNITED STATES PATENT OFFICE.

FOREST H. MONTGOMERY, OF EAST ORANGE, NEW JERSEY.

ATTACHMENT FOR ADDING-MACHINES AND TYPE-WRITERS.

1,221,568.

Specification of Letters Patent.

Patented Apr. 3, 1917.

Application filed March 30, 1916. Serial No. 87,814.

To all whom it may concern:

Be it known that I, FOREST H. MONTGOMERY, a citizen of the United States, residing at East Orange, county of Essex, and State of New Jersey, have invented certain new and useful Improvements in Attachments for Adding-Machines and Type-Writers, of which the following is a specification.

10 This invention relates to attachments for adding machines and typewriters.

The present improvements are adapted for use on adding machines, typewriters, combined adding machines and typewriters, 15 and other machines generally similar thereto.

The present invention is designed to facilitate the posting of a continuous ledger sheet and a separate bill or statement to the 20 end that the statement discloses only the transactions of the current month and their transcription in duplicate on the ledger sheet so that both entries are made at the same time by the machine, due to the intermediate position of a sheet of carbon paper. The 25 entries for the current month, or any particular month, may require only two or three lines and it has been proposed heretofore in mechanical posting devices to provide for the foldover statement and ledger sheet for this work, thus necessitating a new ledger sheet for each new statement sheet. By the use of a separate statement sheet or bill and a separate ledger sheet, a single 30 ledger sheet may be used month after month, accumulating items from time to time, until it is entirely covered with entries struck through a carbon sheet when the entries are placed on successive statements 35 entered from time to time to show the different month's transactions.

The present improvements are particularly designed for facilitating combined statement and ledger sheet posting, although I wish it understood that they are not restricted to such use and that the different improvements utilized in the work hereinafter set forth may be independently, or jointly, used for other purposes on typewriters, adding machines, combined adding machines and typewriters, bill posting or statement making machines and all other machines analogous thereto and I do not limit myself to the uses hereinafter specified 50 nor otherwise than as pointed out in the respective claims.

In practice, a ledger sheet is usually wider than the statement sheet and the position on the ledger sheet for a given entry is usually on a different line, ordinarily higher up, considered from top to bottom of the sheet, than a line on which the given entry should appear on the statement. As heretofore practised, the operator has to meet this condition of two sheets of paper of different widths and a carbon sheet of a width different from the ledger and statement sheets and, also, the necessity for making the entry at different positions, higher or lower, on the two sheets and that the entry 60 must follow the preceding entry on each given sheet.

To meet these conditions, it is necessary to align vertically the ledger sheet and then to properly align vertically the statement sheet so that the vertical column lines on the two sheets will exactly register, even though a carbon sheet is between the ledger sheet and statement sheet. It is also necessary to ascertain the line of entry of the 70 ledger sheet and then shift the statement sheet upwardly or downwardly, as the case may be, to a corresponding line for entry on the statement sheet. As the last visible part of each entry is usually made on the 75 extreme right margin of the statement sheet, heretofore this line of entry would be 80 invisible on the ledger sheet as it will be entirely covered up by the statement sheet and carbon sheet so that the preceding entry 85 is concealed.

The present improvements overcome the foregoing difficulties by the provision, first, of means for automatically printing on the ledger sheet at the right of the margin of 90 the statement sheet a line or other indicia which indicates the last line of entry on the ledger sheet so that this indicia or line is exposed and serves as a guide for the up and down adjustment of the statement sheet to bring the latter to the proper position for the addition of the balance and items of the current month to be printed on the statement sheet, despite the fact that the carbon sheet covers up the items on the ledger sheet, 100 leaving only the indicating line or mark exposed to serve as a guide.

The present invention obviates the other difficulty previously experienced and insures rapidity and accuracy in the vertical 105 alignment of the statement sheet so that the vertical column lines thereon will properly

register with the corresponding lines on the ledger sheet despite the fact that these latter lines are covered by the carbon sheet. To that end, I provide an improved means constituting a secondary vertical alinement guide which constitutes an abutment for either the right-hand or left-hand margin of the statement sheet.

My improved secondary vertical alinement guide may be used in connection with the platen of any writing machine, adding machine, or number printing or other like machine by itself and it may be combined, relatively adjustable or otherwise, with any preferred or ordinary paper guide on the carriage. This secondary vertical alinement guide may be combined with, or used separately from, a paper finger and if used therewith, may be connected thereto or mounted separate therefrom; other modifications could be resorted to, as I am the first, so far as I am aware, to provide a vertical alinement guide, serving as an abutment for the margin of the paper and disposed adjacent to the platen for that purpose, whether such abutment alinement guide be stationary, adjustable, attached to, or combined with, a paper finger guide.

So far as I am aware, I am the first to provide means for printing, in off-set or spaced relation to the printing section of a number printing device, an indicia printer, whether the same operate simultaneously with the number printing device or not. Furthermore, I believe myself to be the first to provide a spaced or separated indicia or sign printer so related to, and combined with, a vertical paper alinement guide that the number will be printed on one side of said guide and the indicia, sign, or symbol, printed on the other side of said abutment paper guide to the end that, in effect, the printing is split on opposite sides, considered horizontally, of said abutment paper guide and which results in the number being printed on the outer and narrower sheet, such as the bill or statement sheet, and the sign, symbol, or indicia being printed on the rear or ledger sheet for purposes of line identification.

The showing of the invention in the accompanying drawings, and the description thereof hereinafter appearing, are illustrative, rather than restrictive, of the scope thereof, as the invention is susceptible of various modifications.

In the accompanying drawings:

Figure 1 is a perspective of so much of the platen, rear paper guide, carriage, and printing section of an adding machine, or a combined adding machine and typewriter, as will illustrate the application of the present improvements and their use;

Fig. 2, is a front detail elevation showing the statement sheet shifted laterally and alined by the abutment paper guide and

drawn upwardly for horizontal line identification with the symbol or indicia on the ledger sheet;

Fig. 3, a detail view of the ledger sheet, statement sheet and carbon sheet associated together as they will be just prior to entry in the machine, as in Fig. 1;

Fig. 4, a similar view, showing the sheets around the platen in the position in which they appear in Fig. 2;

Fig. 5 shows the sheets in the position of Figs. 2 and 4 except that a second entry has been made, showing the new balance and the horizontal alinement of the ledger sheet to indicate the position for the next entry thereon;

Fig. 6, a detail plan view, partly in section, illustrating the manner in which the number printing and symbol printing devices split on opposite sides of the vertical alinement paper guide;

Fig. 7 illustrates the operation which is performed by such splitting of the printing as in Fig. 6;

Fig. 8 is a detail perspective of a vertical alinement paper guide connected to a paper finger; and

Fig. 9 is a view of the vertical alinement paper guide alone.

Referring first to Fig. 1, 1 is a part of the carriage, 2, the platen, 3, the table or paper support and 4, the ribbon and ribbon reel, all of which may be of any construction. The usual rubber rolls which press the paper against the platen, are controlled by the finger-piece 5. The rear paper guides 6 and 7 lie on the paper support or table 3 and are adjustable independently of each other lengthwise of said table or support and locked thereto by means, not shown, adapted for release or setting by the devices 8. Either one, or both, of these paper guides may be used in the operations hereinafter set forth. Carried by the carriage 1 adjacent the platen 2, is a bar or strip 9.

The secondary or vertical alinement paper guide shown in Figs. 1, 2, 8 and 9, is provided with a flap or abutment face 10 and a base 11, the latter being engaged with the bar 9 and preferably slidably lengthwise thereon and frictionally or otherwise engaged therewith so that the said paper guide will be, or may be, held at any point to which it may be adjusted on the bar 9. My invention is not limited, however, in this respect, to a paper guide which is adjustably mounted, but consists, broadly, of a vertical alinement paper guide adapted to serve as an abutment for the margin of the sheet, whether the paper guide be used at the right or the left of said sheet. A portion of the edge may be curved as at 12, so as to conform closely, without touching, to the platen 2 and the papers thereon without, however, interfering with the part 10 serving as an alining

abutment for the edge of the paper. I may combine with the paper guide 10 a paper finger which may be positively connected thereto, as shown at 13 in Fig. 8, or which 5 may be an entirely separate device, either stationary or adjustable, and, the paper guide may be used with or without the use of the paper finger 13. In Fig. 9, I have shown the paper abutment guide 10^a alone. 10 The paper guide 10, or 10^a, may be provided with an alining edge 14 which can be used in connection with the usual scale or straight edge on the machine for horizontal alinement where the type strike on the 15 paper.

Referring to Fig. 1, and to Fig. 6, I have shown printing segments constituting, considered generally, a number printing section 15 such as used, for instance, on the 20 well-known "Ellis" adding machine. These printing segments are adapted to strike the paper as shown in Fig. 6, when the carriage is in proper position and will then deliver their imprint at the left of the paper guide 25 10 to print upon the statement sheet the total or item. Heretofore it has been proposed to provide a signal or symbol printer in connection with these printing segments and in other machines signal printers have 30 been used with other number printing devices. My improvement in that respect consists in providing a sign, signal, or symbol printing device 16 which is off-set or spaced laterally away from the printing section 15, 35 as shown in Fig. 6, so that it will print to the right of the paper guide 10, whereas the printing segments will print to the left thereof, thus, in effect, bringing about a split in the printing and causing the number 40 to be printed on the statement sheet and the sign or symbol which is indicated at 17 to be printed on the ledger sheet. So far as I am aware, I am the first to provide means for this purpose whether the number 45 printing and symbol printing devices be considered alone, or, combined with the paper guide such as generally shown at 10. This symbol printer and the splitting of the printing overcomes the defect heretofore 50 existing and affords an absolute guide, for purposes of line identification, despite the fact that the previous entry on the ledger sheet is completely covered.

Assuming that the work to be performed 55 merely contemplates the use of a ledger sheet 18, a statement sheet 19 and carbon sheet 20, these are first associated to aline the sheets along the top and left hand edges, as shown in Fig. 3. The sheets are then inserted in the machine, using the right-hand paper guide 6 on the back of the carriage to coöperate with the right-hand edge of the ledger sheet 18. The sheets are then turned 60 up to the position shown in Fig. 1. The symbol or sign 17 indicating the line of last

entry on the ledger sheet being exposed and plainly visible, the platen is turned so that the part 14 is opposite this line. There is now a vertical and horizontal alinement of the wider or ledger sheet 18. The statement 70 sheet 19, however, is too far to the left and not in proper horizontal alined position, because the statement sheet 19 usually has a deeper heading than the ledger sheet and corresponding horizontal lines would, therefore, be below correct positions on the ledger sheet. The statement sheet 19 is consequently taken hold of and drawn up to the position of the ordinary commonly used horizontal line guide on the carriage, the 75 lever 5 having been moved to release the gripping of the paper so that this shifting of sheet 19 can be obtained. When pulling the sheet 19 vertically, it is also shifted laterally to bring its right-hand margin against 80 the paper guide 10. This having been done, as shown in Figs. 2 and 4, the statement sheet 19 is thus vertically and horizontally alined so that its registration with the ledger sheet 18 will be accurate. The pressure 85 rolls controlled by the lever 5 are then thrown into holding position so that the sheets 18, 19 and 20 are securely held to the platen, as in Fig. 2.

As shown in Fig. 4, the sheets are in 90 proper position for the next entry, the balance on the old account having been previously printed by the printing section 15 on the first line of the statement, as shown in Figs. 2, 4 and 7 which also prints the sign 100 17 if not already appearing on the ledger sheet. It will be noted that the last entry on the statement sheet, which is also struck through to the ledger sheet, is \$500 in the charge column and \$500 in the balance column with the mark 17 printed only on the ledger sheet 18 at the right and directly opposite the balance column.

In Fig. 5, the sheet shows a second entry 110 for the current month and the new balance and also the printing of the mark 17^a on the ledger sheet 18 which will thus indicate the position for the next entry on the ledger sheet when the latter is put into the machine 115 at some future date.

Having thus described my invention, what I claim as new and desire to secure by Letters Patent, is:—

1. In a printing machine having a platen, the combination with a freely projecting 120 vertical alinement paper guide disposed adjacent the front of said platen and adapted to serve as an abutment for an edge of one or more outer sheets of a narrower width than the under sheet, at the front of the 125 platen, and means for holding an under sheet or sheets against the platen, outside or beyond the edges of the outer narrower sheet independently of the outer sheet, whereby the outer sheet may be freely ad- 130

- justed alined and guided by the paper guide independently of the under sheet.
2. In a printing machine having a platen, a freely projecting vertical alinement paper guide disposed adjacent the front of said platen and adapted to serve as an abutment for an edge of that portion of the paper which is at the front of the platen, and a paper finger connected to the paper guide said paper guide being innermost in relation to the paper finger whereby the paper finger is adapted to bear on the under sheet while the paper guide engages the edge of an outer sheet.
- 15 3. In a printing machine having a platen, a freely projecting vertical alinement paper guide disposed adjacent the front of said platen and adapted to serve as an abutment for an edge of that portion of the paper which is at the front of the platen, and a paper finger connected to the paper guide, said paper guide being innermost in relation to the paper finger whereby the paper finger is adapted to bear on an under sheet 20 while the paper guide engages the edge of an outer sheet, the alinement paper guide and paper finger being adjustable as a unit in the direction of the length of the platen.
4. In a printing machine having a platen, the combination with a vertical alinement paper guide serving as an abutment for the edge of the paper, of a number printing device comprising means for printing a number at one side of the said paper guide and 35 means for printing a sign or symbol at the other side of the paper guide in spaced relation to the number which is printed.
5. In a printing machine having a platen, the combination with a vertical alinement paper guide serving as an abutment for the edge 40 of the paper, of a number printing device comprising means adapted for simultaneously printing a number at one side of the said paper guide and for printing a sign or symbol at the other side of the paper guide in spaced relation to the number.
6. In a printing machine having a platen, the combination of a rear side edge guide for one edge of a plurality of sheets of different widths, a front side edge gage for an 45 edge of the narrower sheet, and means positioned and adapted for holding the plurality of sheets against the platen, when the said sheets are initially adjusted thereon and for engaging only the wider sheet when the narrower sheet is individually adjusted and gaged by the front side edge gage.
7. In a printing machine having a platen, the combination of a rear side edge guide for one edge of a plurality of sheets of different widths, a front side edge gage for an opposite edge of the narrower sheet, and means positioned and adapted for holding the plurality of sheets against the platen when the said sheets are initially adjusted thereon and for engaging only the wider sheet when the narrower sheet is individually adjusted and gaged by the front side edge gage.
8. In a printing machine having a platen, the combination of a rear side edge guide for one edge of a plurality of sheets of different widths, a front side edge gage for an edge of the narrower sheet, means positioned and adapted for holding the plurality of sheets against the platen when said sheets are initially adjusted thereon and for engaging only the wider sheet when the narrower sheet is individually adjusted and gaged by the front side edge gage, and additional means positioned and adapted for holding the wider sheet against the platen at all times.
9. In a billing machine, means for holding two sheets in superimposed relation with their edges offset, means for printing a number on one sheet adjacent its edge, and means for simultaneously printing an identifying symbol on the other sheet only.
10. In a billing machine, means for holding two sheets in superimposed relation with their edges offset, means for printing a number on the outer sheet adjacent its edge, and means for simultaneously printing an identifying symbol on the under sheet only.
11. In a billing machine, a side edge guide adapted to serve as an abutment for the edge of the outer one of a plurality of sheets so that the edges of the sheets may be relatively offset, means for printing a number on an outer sheet adjacent an edge thereof, and means for simultaneously printing an identifying symbol on the under sheet only.
12. In a billing machine, a platen, a side edge paper guide, and a number printing device comprising means for printing a number at one side of an imaginary line running through said side edge guide and means for printing a sign or symbol at the other side of said imaginary line.
- In testimony whereof, I hereunto affix my signature.
- FOREST H. MONTGOMERY.
